SNOW REMOVER

Filed April 23, 1920

Inventor
James Lagomarsino
By Dodson & Roe
Atlys.

UNITED STATES PATENT OFFICE.

JAMES LAGOMARSINO, OF CHICAGO, ILLINOIS.

SNOW REMOVER.

Application filed April 23, 1920. Serial No. 375,957.

To all whom it may concern:

Be it known that I, JAMES LAGOMARSINO, a citizen of the United States, residing in Chicago, county of Cook, and State of Illinois, have invented a certain new and useful Improvement in Snow Removers, of which the following is the specification.

My invention relates to that class of devices which are designed to remove the snow from the streets without the necessity of manual operation other than is afforded by the driver of the machine. These devices are subject to the greatest abuse and rough usage due to the conditions under which they operate hence constructions which would be satisfactory in a shop quickly become valueless in use.

My invention has for its object to provide a construction which will survive the roughest usage as well as abuse and still be usable and has for its further object to provide a device which may be detachably secured to a truck, or may, if desired, be constructed as an integral part of the truck, and has for its further object to provide means whereby the snow and ice removed from the street may be deposited upon other trucks so that the work of the machine can be practically continuous.

Devices of this kind with which I am familiar, which are provided with means for accommodating the shovel to the inequalities of the surface of the roads such as manholes, cobblestones, and the like are provided with mechanism which would work satisfactorily in a factory but which when subject to the snow and ice and melting and freezing soon become so rusted as not to be operative.

In my improved construction I provide a shovel which is so arranged that it will automatically take care of uneven road conditions by providing a construction which will not be injuriously affected by its use under the conditions for which it is designed. Obviously as these conditions are under the snow, they would be invisible to the driver, so that unless the device is entirely automatic, it would be of little value.

My means of accomplishing the foregoing objects may be more readily understood by having reference to the accompanying drawings which are hereunto annexed and are a part of this specification in which:

Figure 1 is a side elevation of my improved device.

Fig. 2 is a top or plan view of the same.

Fig. 3 is a transverse section through the conveyor.

Fig. 4 is a sectional view of the shovel. 60

Fig. 5 is a sectional view of the ice pick.

Fig. 6 is an enlarged detailed view from the side, showing the pivoting of the ladder to the frame. Fig. 7 is a top or plan view of the same. 65

Similar reference numerals refer to similar parts throughout the entire description.

As shown in the drawings, 1 is the motor truck, provided with suitable wheels 2 which are driven by any of the usual means 70

of propulsion (not shown). My improved snow remover comprises, as shown, an outwardly extending ladder formed of beams 4 and 5, these beams being connected together by rollers 46, 47, 48 and 49 in spaced 75

relation to each other and upon which the belt 7 of the conveyor travels. At the forward end of the ladder formed by the beams 4 and 5 I mount my improved shovel which comprises a plate 25 which is provided with 80

upwardly extending shoulders or portions 26 which extend the entire length of each side of the plate. On the inside of these shoulders are formed guides 27 in which the shovel 8 slides. I provide a reinforce- 85

ment for the shovel by means of longitudinally extending shoulders 28 and 29 which are fitted to the guides 27 being held in position by means of the walls 23 and 24 on each side of the guides 27. This construc- 90

tion enables the shovel to resist the great strain under which it operates when beyond the guides 27. In the plate 25 I form slots 9 which extend clear through the plate so 95

that instead of the snow, ice or water lodging in them and preventing the operation of the shovel they will pass freely through leaving the slot clear. Pins 10 are riveted to the shovel 8 and extend through the slots 9. The function of these is not to hold the 100

shovel against the plate 25 which is accomplished by the guides 27 but is to provide a support for one end of springs 11 the other ends of which are secured to lugs 28 which are fastened to the underside of the 105

plate 25 in any desired or convenient manner. These springs serve to hold the shovel 8 normally in the projected position shown in Fig. 4. The point 14 of the shovel may be constructed as shown so as to dig into 110

the snow. The lower end of the ladder is provided with a pair of wheels 16 mounted

upon a suitable axle 16 so as to sustain the weight easily. This axle is provided with a central pivot so that its direction may be shifted. The upper end 17 of the ladder 5 is pivotally secured by means of roller 49 to beams 18 and 19 mounted upon the top of the truck 1 through the center of which the conveyor belt 7, which is supported by roller 60 passes. Brackets 51 and 52 being 10 formed on the forward end of the beams 18 and 19, in which are mounted the ends of the roller 49. Upon one end of this roller is mounted a sheave 50.

A wire cable 20 is provided to elevate the 15 remover when not in use, the cable being secured to the lower end of the ladder, from which position it passes up over the sheave 50 and is wound upon a drum 21 indicated in Figure 2. The wheels 15 are guided by 20 means of a pair of wire cables 30 which are attached to the axle 16 and which pass over suitable sheaves (not shown) to the motor truck so that the direction of the remover may be shifted by the operator as the motor 25 truck moves. An aperture 22 is provided in the shovel to receive a bolt to fasten it to the plate 25, so as to prevent its sliding movement when it is desired.

The operation of the device is as follows: 30 When the truck arrives at the place from which the snow is to be removed, the ladder is lowered into the position shown in Figure 1, through the medium of the wire cable 20, the drum 21 being unwound so as to let 35 wheels 15 rest upon the ground.

These wheels are arranged so as to bring the point 14 of the shovel 8 practically in the same plane as the road bed which is to be cleared. The motor truck is then started 40 and as it moves forward, obviously the point of the shovel is pushed under the snow which slides up over the surface of the shovel, striking the conveyor belt 7 on the ladder which carries it up to the top of the motor 45 truck and along between the beams 18 and 19 to their overhanging ends at the rear of the truck. This extension permits the wagon or truck which is to be loaded to drive under the conveyor to be driven under the extension 50 so the conveyor belt 7 will drop the snow into the empty vehicle without the necessity of the truck carrying the remover stopping at all.

Should the point 14 of the shovel strike 55 any unevenness in the road, the springs 11 permit the shovel to slide inwardly, the slots 9 being provided for this purpose, the pins 10 preventing its moving too far. This movement permits it to jump any obstruction 60 with comparative ease and even without the operator being aware of the unevenness.

Suitable gears are provided to be driven 65 from the motor by any convenient means (not shown), and these gears drive a roller

which in turn imparts its motion to the conveyor belt 7.

Where there has been a hard storm and considerable ice is encountered, it is necessary to provide teeth on the shovel which is 70 accomplished by a duplicate shovel which has a plurality of sharp teeth or points as clearly illustrated in the detail view, Fig. 5. When the remover is provided with this form of shovel, it will successfully remove 75 an accumulation of icy snow which the plain shovel would be unable to remove.

Having described my invention what I regard as new and desire to secure by Letters Patent of the United States is:

1. In a device of the character described, the combination of a pair of beams rigidly mounted upon the top of a self-propelled vehicle and extending longitudinally thereon, a ladder pivotally secured for vertical movement to the forward end of said beams, a plurality of rollers in said beams and ladder, a conveyor belt mounted upon said rollers, a plate of the same width as the ladder secured to the lower end thereof, shoulders 80 on each edge of said plate which extend longitudinally its entire length, guides formed in said shoulders, a shovel slidably mounted upon said plate, having reinforcements along each edge which are fitted to and slide 85 in said guides, there being slotted openings extending through said plate, adjacent its upper end, pins secured to the lower side of said shovel which extend through said slots, lugs formed on the lower side of said plate, 90 springs which connect said lugs to said pins, whereby said shovel is held normally in a projected position.

2. In a device of the character described, the combination of a pair of beams rigidly 105 mounted upon the top of a self-propelled vehicle and extending longitudinally thereon, a ladder pivotally secured for vertical movement to the forward end of said beams, a plurality of rollers in said beams and ladder, a conveyor belt mounted upon said rollers, a plate of the same width as the ladder secured to the lower end thereof, shoulders 110 on each edge of said plate which extend longitudinally the entire length, guides formed in said shoulders, a shovel slidably mounted upon said plate, having reinforcements along each edge which are fitted to and slide in 115 said guides, there being slotted openings extending through said plate, adjacent its upper end, pins secured to the lower side of said plate, springs which connect said lugs to said pins, whereby said shovel is held normally in a projected position, means carried by the fixed beams to elevate the ladder vertically.

In witness whereof, I have signed the foregoing specification.

JAMES LAGOMARSINO.
